[57] CLAIM

The ornamental design for a splint, as shown and described.

DESCRIPTION

FIG. 1 is a top plan view of a splint, showing my new design;

FIG. 2 is a side elevational view thereof;

FIG. 3 is an end elevational view thereof;

FIG. 4 is a front perspective view thereof;

FIG. 5 is a front perspective view showing the splint applied to a patient, with the broken line disclosure being for illustrative purposes only and forming no part of the claimed design.

FIG. 1

FIG. 2

FIG. 3

FIG. 4

FIG. 5
